UNITED STATES PATENT OFFICE.

THOMAS S. SPIVEY, OF CINCINNATI, OHIO, ASSIGNOR TO THE VICTOR SAFE AND LOCK COMPANY, OF SAME PLACE.

PERMUTATION-LOCK.

SPECIFICATION forming part of Letters Patent No. 372,498, dated November 1, 1887.

Application filed May 3, 1887. Serial No. 236,926. (Model.)

To all whom it may concern:

Be it known that I, THOMAS S. SPIVEY, a citizen of the United States, residing at Cincinnati, in the county of Hamilton, State of Ohio, have invented certain new and useful Improvements in Permutation-Locks, of which the following is a specification, reference being had therein to the accompanying drawings.

This invention relates to that class of permutation-locks whose bolts carry the spindle, driving-disk, and tumblers; and the first part of my improvements comprises a specific combination of devices whereby a cheap, simple, and perfectly reliable lock is afforded, as hereininafter more fully described.

The second part of my improvements consists in providing the spindle with a permanent and a detachable pointer, the former of which is designed to mislead a burglar by indicating a false combination, while the application of the detachable pointer to the spindle enables the owner or other custodian of the safe to turn the disk and tumblers to the correct combination in a few moments, said pointers being used with any lock having a graduated dial-plate that is either numbered or lettered, as hereininafter more fully described.

In the annexed drawings, Figure 1 is a front elevation of the dial-plate of my lock, the shank of the spindle being sectioned, the knob of the same being indicated by the dotted circular line and the true pointer being set to show the correct combination of the tumblers. Fig. 2 is an enlarged horizontal section of the lock, taken in the plane of the numerals III and IX of the preceding illustration, the bolt being advanced or "shot." Fig. 3 is a rear elevation of a portion of the lock-case, the cap detached therefrom, the bolt being retracted and the gates of the disk and tumbler engaged with the fixed stop. Fig. 4 is a similar elevation, but showing the bolt advanced or locked and the disk and tumbler so shifted as to break the combination. Fig. 5 is an elevation of the slotted end of the bolt. Fig. 6 is a sectionized plan showing the method of attaching the inner washer to the tubular tumbler-stump. Fig. 7 is an enlarged plan of the gated tumbler. Fig. 8 is an enlarged elevation of a portion of the front of the spindle-hub, the shank

thereof being sectioned. Fig. 9 is a front elevation of a modification of my invention. Fig. 10 is an enlarged horizontal section through the same. Fig. 11 is a modification of the dial-plate.

Referring to Fig. 1, A represents a portion of a drawer or safe door or other lid or covering to be securely locked, and B is a dial-plate, secured to the outside of said door by screws b or otherwise, said plate having a circle, b', punched or engraved or permanently inscribed thereon, the Roman numerals I II, &c., being arranged outside of said circle, while graduations radiate inwardly from the same. I prefer making this dial exactly like a clock-face, the Roman numerals running consecutively from I to XII to indicate hours, while suitable graduations are arranged between each of said numerals, which graduations are for the minutes, and may be numbered as shown between XII and I. Furthermore, this fixed dial-plate has a horizontal slot, b'', (seen only in Fig. 2,) which slot is traversed by the operating-spindle C, the external portion of which comprises a hub, D, shank E, and handle or knob e, said hub having a false pointer, F, either cast therewith or otherwise rigidly secured thereto. The periphery of hub D has a series of radial screw-threaded sockets, d, to receive the screw-threaded end of the true pointer G, which latter is usually a short wire that can be readily carried in a pocket-book, and to more completely disguise its use said wire can be made to resemble an ordinary metallic tooth-pick. These sockets are preferably numbered on the outer face of the hub, eight of such numbers being seen in Fig. 1, while twelve are suggested in Fig. 8; but a greater or less number can be used, if desired.

Spindle C traverses the horizontal slot a of the door and a similar slot, h, of the lock-case H, the latter being closed at the back by the cap-plate I; and the inner end of said spindle has a square arbor, e, that carries the driving-disk J and rotatable washer K, which washer is held in place by a fastener, k. Driving-disk J has a gate, j, and pin j', which latter operates the shiftable pin l' of the tumbler L, said tumbler being gated at l, and having a series of perforations, l'', into either one of which

said shiftable pin can be screwed, for the purpose of changing the combinations in the usual manner. (See Fig. 7.) This tumbler turns freely upon the tubular stump n , projecting from the lock-bolt N , said stump being grooved longitudinally on one side, as seen at n' in Figs. 5 and 6, to admit the tongue o of a stationary washer, O , which washer is interposed between the driving-disk J and tumbler L , and as many of these fixed washers and revolving tumblers may be added as the special duty of the lock requires.

i in Figs. 2 and 3 represents the fixed stop for the gates to engage with, which stop is here shown as a screw, wherewith the cap-plate I is secured to the lock-case H ; but in Fig. 4 said stop is shown as a flange or rib, i' , projecting inwardly from the end of said case. Either of these devices or any other fixed bearing can be used to take the place of said stop. n'' is a longitudinal slot in the inner end of the bolt N , which slot is of such a size as to clear the bearing or stop i .

The method of operating this lock is as follows: When the bolt N is pulled back, the now coincident gates of the driving-disk, tumbler, and bolt occupy the position seen in Fig. 3 and indicated by dotted lines in Fig. 2, the screw i serving as a stop that limits the retraction of said bolt. If the knob e is not turned either to the right or left, it is evident the bolt can now be readily advanced or retracted by the spindle C for the purpose simply of opening or closing the door; but if it is to be securely locked said bolt must first be shot, and then said knob be turned indiscriminately so as to scatter or break the combination. This condition of the lock is seen in Fig. 4, wherein it is shown that the gates j l are no longer in line with each other. Said illustration shows, also, that the ungated portions of the disk and tumbler bear against the stop i' , and thereby prevent the bolt being retracted until the combination is restored. In the present case but one tumbler, L , is used, and it will, for the purpose of illustration, be supposed that the pin l' has been so inserted in said tumbler as to cause the gates j l to be coincident with the slot n'' of the bolt only when the true pointer G has been inserted in the socket 5 of the hub D and the handle e turned until said pointer reaches the second graduation or mark beyond the numeral IX, as seen in Fig. 1.

The custodian of the safe can keep a record of this combination by making a very fine lead-pencil mark on his watch or clock directly opposite two minutes past nine, and then simply remembering that socket 5 is to be used. Therefore, bearing the number of the socket in his mind or having it written on a slip of paper, and with the true pointer G in his pocket or pocket-book and an almost imperceptible record of the combination on his clock-face at home, he feels assured the safe cannot be opened during his absence.

If a clandestine attempt should be made to open the lock, the false pointer F would deceive the burglar, because it can by no means be made to indicate the combination, and if 70 said pointer should be arrested at the second mark beyond the numeral IX the gates would not be in line. Foiled in this effort, the burglar might whittle a small wooden pin and insert it in one of the sockets d and then go 75 carefully around the dial-plate without success, because the pin would not always get in the proper socket, and by providing the hub with two or three dozen such sockets it would be almost impossible to find the combination; 80 but the custodian of the safe has simply to look at his clock before he leaves home to see that the combination is set at two minutes past nine, and when he arrives at his place of business the true pointer G is taken out of his 85 pocket and screwed into the socket 5. Knob e is now turned until said pointer reaches the second graduation-mark beyond the numeral IX, or, in other words, indicates two minutes past nine, which act brings the gates j and l 90 in line with the slot n'' of the bolt, and the latter is then retracted, as seen in Fig. 3, and the safe-door is opened.

The above is a description of a very cheap and simple form of my lock having a single 95 tumbler; but if three tumblers should be used three different combinations would be necessary. They could be arranged thus: the first tumbler for five minutes past one; the second tumbler for ten minutes past two, and the third 100 tumbler for fifteen minutes past three. This arrangement, however, is merely suggestive, not arbitrary, as the combinations need not be set in such a regular order; but it is preferred to have them progressive, or, in other words, 105 to read in the same direction a hand travels around the face of a clock.

Fig. 9 shows another modification of my invention, in which the spindle C carries a wheel, P , that gears with another wheel, R , on a shaft, S , whose outer end has a socketed hub, D , to receive the true pointer G , the false pointer being omitted. Pointer G travels in front of a dial, B , that is graduated in any suitable manner, but preferably as shown in Fig. 1, 110 and this dial has two lugs, T T' , the lug T having a screw, t , passed through it and then engaged with the case U , within which the gearing is inclosed. The other lug, T' , is slotted longitudinally at t' , to receive a screw, 115 t'' . u is a slot in the case U , to permit the shifting of shaft S . By disengaging the screw t and then slackening the other screw, t'' , the dial B and wheel R can be shifted to the left for the purpose of throwing said wheel out of 120 gear with the wheel P . Wheel R can then be turned the distance of a single tooth and re-engaged with wheel P , thereby adding another 125 change to the combination of the lock, after which act the dial is fastened in place with the 130 screws t t'' . After all the teeth of wheel R have been used for setting up new combina-

tions, the other wheel, P, can be utilized in the same manner, thus affording an almost endless set of changes.

Another but inferior modification of my invention is seen in Fig. 11, where the Arabic numerals are arranged outside the circle b', while the gradations between said numerals are lettered a b c d.

The right is reserved of entering in a future application the combination-changing devices seen in Figs. 9 and 10 of the annexed drawings.

I claim as my invention—

1. In combination with a permutation-lock having a slotted case, A a, and stationary slotted dial B b", the reciprocating bolt N, fitted within said case and provided with a slot, n", and rearwardly-projecting tubular stump n, said stump being traversed by the spindle C, whose hub D conceals the slot b" of the fixed dial, the inner end of said spindle being furnished with a driving-disk, J, having a gate, j, and pin j', one or more gated tumblers, as L l l', being journaled upon said stump n, and a stop, i, being provided within the lock-case, as herein described, and for the purpose stated.

2. A permutation-lock spindle provided

with a hub having a series of lettered or numbered peripheral sockets for the reception of a detachable pointer, substantially as herein described.

3. A permutation-lock spindle provided with a hub having a permanent false pointer and a series of lettered or numbered peripheral sockets for the reception of a detachable true pointer, substantially as herein described.

4. A permutation-lock provided with a fixed dial, as B, slotted at b" to allow a free reciprocation and turning of the spindle C, which spindle operates the bolt, driving-disk, and tumblers, as herein described, and has an external hub, D, that conceals said slot, substantially as set forth.

5. The combination, in a permutation-lock, of a spindle provided with an external hub, a detachable pointer, and means for readily securing said pointer to said hub, for the purpose described.

In testimony whereof I affix my signature in presence of two witnesses.

THOMAS S. SPIVEY.
